SAFETY RAZOR

Paul L. Phillips, Hartford, Conn.

Application February 15, 1938, Serial No. 190,630

20 Claims. (Cl. 30—75)

My invention relates to safety razors.

It has among its objects to provide an improved blade connecting and supporting structure. Other objects are to provide an improved construction whereby a blade is accurately and securely positioned on a holder in an improved manner, and to provide such a construction wherein the blade is readily and quickly connectible and removable at will. Further objects of my invention are to provide an improved razor construction, and also one wherein the parts of the holder, and also the razor blade, are so improved that, in addition to the above advantages, they cooperate in an improved manner to enable improved results to be obtained during shaving and the handling of the razor incident thereto, while also enabling the razor to be very inexpensively produced. These and other objects and advantages of my improved construction will, however, hereinafter more fully appear.

In the accompanying drawing, I have shown for purposes of illustration certain embodiments which my invention may assume in practice.

In the drawing,—

Figure 1 is a perspective view of a razor with the backing member raised to expose the blade therein, a portion of the blade also being broken away to facilitate illustration;

Fig. 2 is a similar perspective view, the backing member being removed and the blade being shown in process of connection to the guard member;

Fig. 3 is a view similar to Figure 2 but showing the blade as it approaches connected position and is about ready to snap into the position shown in Figure 1;

Fig. 4 is a plan view of the guard and blade shown in Figures 2 and 3 but with the blade in connected position;

Fig. 5 is an enlarged sectional view on line 5—5 of Figure 4;

Fig. 6 is a plan view of the blade removed from the guard;

Fig. 6a is an enlarged detail section of the blade taken on line 6a—6a of Figure 6;

Fig. 7 is an enlarged detailed sectional view on line 7—7 of Figure 4, showing the co-operating guide structure on the blade and guard;

Fig. 8 is a detail transverse section of the assembled razor taken on line 8—8 of Figure 1;

Fig. 9 is a view similar to Figure 7 showing a modified construction;

Fig. 10 is a similar view showing a further modified construction;

Fig. 11 is a view similar to Figure 4 showing a modified guard and blade structure;

Fig. 12 is an enlarged sectional view on line 12—12 of Figure 11;

Figure 13 is a plan view of the blade shown in Figure 11, and

Figure 14 is a transverse sectional view similar to Figure 8 and including the guard but showing this modified construction.

10 In the illustrative construction shown in Figures 1 to 8, I have shown a razor comprising a guard 1 and cooperating backing member 2 connected thereto by a member 3 extending into a handle 4 and adapted to be threaded to a usual knob 4a in a usual manner; the guard 1 and backing member 2 each herein being of an improved construction and cooperating with an improved blade 5, as hereinafter described.

Referring first to the guard 1, it will be noted

20 that the same is provided with an improved longitudinally extending centrally located blade connecting means, herein a raised portion 6 provided with an aperture 7 midway between its ends through which the connecting member 3 of the backing member extends, and herein also of greater width than the diameter of this aperture 7. Moreover, it will be noted that the portion 6 is raised above the curved face 8 of the guard 1 so that the same is substantially thicker

25 than the blade 5, this portion 6 as shown being substantially twice as thick as the blade. Further, the end parts of the portion 6 are suitably spaced inward from the ends of the guard 1 in such manner as to provide a substantial support 5a for the blade at each end thereof. The ends of the portion 6, while capable of assuming other forms, are herein also rounded, as shown at 9, while the top of this portion 6, although not limited thereto, is also shown herein as flat.

30 Attention is also directed to the fact that parallel longitudinal side walls 10 are provided on this portion 6 and that these are herein grooved or undercut, as shown at 11, in such manner as to provide on opposite sides of the portion 6 extending throughout the length thereof, longitudinal blade receiving slots, preferably somewhat upwardly flared at their opposite ends, as shown at 11a, to facilitate entry of the cooperating blade portions hereinafter described. Referring to

35 Figure 7, it also will be observed that each groove or slot 11, while not limited thereto, in a preferred cross section comprises a bottom upwardly and inwardly sloping surface 12, herein extending beyond the plane of the walls 10, a top sloping surface 13, shorter than the surface 12 and ex-

tending upwardly and outwardly, and a short vertical surface 14 and connecting the inner ends of the sloping surfaces 12 and 13.

Cooperating with the improved connecting portion 6, just described, is the improved blade 5. Herein, this blade, which is preferably formed of thin resilient steel, is provided with a central longitudinal slot or recess 15 closed at its ends, the opposite longitudinal edges 16 of which are straight and adapted to be received in the opposite undercuts or grooves 11 in the portion 6 hereinafore described. Each slot edge 16 is also relieved along the top and bottom corners thereof and preferably, as herein shown, to form on these edges oppositely directed, herein oppositely tapered, surface portions 17, corresponding to the surface 12 in the slot, and preferably of equal length and taper to facilitate manufacture, and spaced by an intermediate untapered portion 17a; these portions 17 being adapted to cooperate with the surfaces 12, 13 of the slot 11 to prevent lateral displacement of the blade relative to the guard and take up inequalities in manufacture, while accurately and securely locating and centering the blade relative to the guard when pressed down by the backing member 2, as hereinafter described. Further, it will be noted that the blade is provided on opposite ends of the slot 15 with openings 18 wider than the slot 15 and exposing the ends of the longitudinal recess edges, while providing transverse lines of ready flexure and locating these advantageously adjacent these exposed ends. Herein, while not limited thereto, the openings 18 are substantially semi-circular in shape and conform generally in shape to the ends 9 on the connecting portion 6, either of the openings 18 being adapted to snap over either end 9 as the blade moves from the position shown in Figure 2, through the position shown in Fig. 3, to that shown in Figure 1 in which the remote ends are in the plane of the grooves and behind the ends 9 of the connecting means 6. Here also it will be noted that the blade 5 is preferably provided with end extensions 19 on its opposite ends which extend beyond these openings 18 and are adapted to be supported on the portions 5a on the top surface 8 of the guard 1, while also extending beyond the ends of the latter to provide ready means of raising and transversely flexing the end of the blade from the position shown in Figure 1 to that shown in Figure 3 when the blade is being removed.

Cooperating with the improved guard 1 and improved blade 5 is an improved backing member 2. This member is of generally conventional shape and adapted to cooperate in flexing the blade 5 in a usual manner into the desired position relative to the usual longitudinal edges of the guard 1. However, it will be noted that, instead of having a projection of any sort on its inner face receivable in a portion of the guard 1, this member 2 is provided with a recess in this face. Herein, a slot or recess 20 is provided which extends longitudinally of the guard and is adapted to receive the connecting portion 6 therein. Moreover, the bottom portions 21 along this slot also preferably engage the blade along the edges of the slot 15 therein and closely adjacent the connecting portion 6, in such manner as to press the portions of the blade against the top surface 8 of the guard, and especially the bottom tapered surfaces 12 in the grooves 11, and thereby center and clamp the blade between the guard and backing member, while also minimizing

breakage due to longitudinal flexing of the portions 16, 19 by the backing member. It will also be noted that the depth of the slot 20 herein is also greater than the height of the portion 6, as shown in Figure 8, to insure such clamping. Herein, as in a preferred construction, the slot 20 also is of greater width than the diameter of the portion 3 on the backing member, as shown in Figure 8.

In the use of this improved construction, it is possible for the blade 5 to be very readily and securely connected to the guard. As shown in Figure 2, one end of the blade is slightly flexed transversely by raising its end portion 19 so that this portion will overlie the adjacent end of the portion 6, and so that the edges 16 of the blade slot 15 are in alignment with the bevelled undercuts 11 disposed on opposite sides of the portion 6. When in this position, the blade may obviously be moved readily longitudinally of the portion 6, while holding the portion 19, in such manner as to draw the remainder of the edges 16 into the undercuts 11, the parts then assuming the relation shown in Figure 3. However, when the blade 5 is moved further to the right, i. e. to the position shown in Figure 1, it will be evident that the forward end of the blade will snap down over the rounded end 9 of the portion 6, in such manner that the blade is then securely connected to the guard 1 throughout the length of the blade slot 15 with the recess edge portions on the blade in the grooves in the connecting means 6 and the closed end portions in abutting relation behind the ends 9 thereof. Then, obviously, the backing member 2 may be connected in a usual manner, by extending its member 3 through the aperture 7 into the handle 4 and connecting it in a usual manner by rotation of the usual knob 4a; the edges 21 of the slot 20 in the backing member 2 then also preferably pressing down upon the portions of the blade along and adjacent the connecting portion 6, while the sharpened edges of the blade are flexed downward by the backing member relative to the longitudinal fingered edges of the guard to prepare the razor for use in shaving. Obviously when it is desired to change or sharpen a blade 5, the same can be readily removed following removal of the backing member, by merely raising either of the end portions 19 to clear the end 9 of the connecting portion 6 and moving the blade longitudinally while the end portion is supported on the portion 6, the parts then being again in the relation shown in Figures 2 and 3, and the blade being completely separated from the connecting portion 6 after the parts have passed through the position shown in Figure 2.

As a result of this improved construction, it will be evident that the blade 5 is very accurately positioned on the holder in such manner that uniform shaving results are obtainable. Moreover, due to the cooperating tapered portions on the blade and slot 11, the blade edges are definitely and accurately centered relative to the guard despite variations in manufacture, such, for example, as variations in width of the slots in the blade and guard. Thus, for example, if the slot in the blade is so wide that the portions 17a thereon will not abut the vertical surfaces 14 on the guard, the bevels will obviously still accurately position the blade. The connection of the blade to the holder also prevents all displacement or shifting of the blade relative to the holder during connection of the backing member and conse-

quent inconvenience and possible dulling of the blade, while also facilitating and expediting the connection of the backing member. Further, it is made possible for either end of the blade to be inserted on either end of the guard. Also, this connecting movement, being longitudinal, is such as to minimize the danger of spoiling the blade edges by striking them against the guard. Moreover, with the blade thus connected to the holder with the backing member removed, it is possible for the blade and holder to be rinsed thoroughly without danger of dulling of the blade edges either by contact with the backing plate, or movement relative to the guard, both of which frequently occurred in previous constructions; my improved construction making it possible for the backing member to be removed entirely and the entire blade, the cutting edges of which then spring up, to be rinsed or cleansed effectively while still remaining securely positioned on the guard. It will also be evident that when it is desired to remove the blade from the guard, as for sharpening, this may be readily accomplished by a longitudinal movement in either direction, thereby also minimizing nicking, while such difficulty is still further minimized by the fact that the blade is completely freed from the holder as soon as the edges of the blade slot disengage the side grooves 11 in the connecting portion 6.

Obviously, the construction is also such that either end of the blade may be readily flexed upward in such manner as to provide a ready and convenient means of sliding the blade relative to the guard, the upwardly flexed ends of the blade providing a convenient means for disposing the ends of the recess edge portions tangentially relative to said flexed end and thereby facilitating the entry of the edges of the slot 15 in the grooves 11; while the ends 19 also are readily movable into or out of engagement with the portion 6 and when supported thereon also provide an abutment facilitating blade movement while the user's fingers are disposed out of contact with the cutting edges of the blade. The provision of the portions 21 on the backing plate and the adjacent arcuate blade engaging faces of the back plate, also act to minimize blade breakage, eliminating undue strain on the edges of the slot or recess in the blade, which are disposed in the opposite grooves in the connecting portion 6, while still permitting the blade to be of a simple and inexpensive construction. Attention is further directed to the fact that my improved connection between the blade slot edges and the connecting member 6 is such as to require the use of blades of my improved construction and thus precludes the use of inferior blades which, lacking my improved relieved or bevelled edges along the slot or longitudinal opening therein, obviously will not fit the grooves or slots 11 in the portion 6. For example, a non-beveled blade thinner than the groove would have to have the upper edges of its recess pass under the upper or overhanging walls 13 or 24 of Figures 7 or 9 and thus would have the lower edges of its recess supported on the longer bottom beveled portions 12 or 22 at some point within the overhanging walls 13 or 24 in such manner that the bottom of the blade adjacent the connecting portion 6 would be spaced above the upper face 8 of the guard, and thus would either prevent the backing member from moving down into its normally clamping position or break the blade. Here it will further be noted that by providing opposite-

ly directed surfaces or reverse bevels on the top and bottom edges of the blade slot or longitudinal opening, it is not only made possible to facilitate and cheapen manufacture, but also to connect the blade to the guard with equal facility regardless of which side of the blade is up, while still obtaining the above advantages of my improved construction of blade and connecting means. These and other advantages of my improved construction will, however, be apparent to those skilled in the art.

In Figures 9 and 10, I have also shown modified forms of the improved guiding connection between the connecting means 6 and the blade which may be used if desired. In Figure 9, it will be noted that the slot in the member 6 has a portion 22 generally corresponding to the portion 12 heretofore described, but that a longer vertical portion 23 is provided which extends to a horizontal top guide portion 24. Here, certain of my improved results as regards guiding and positioning of the blade will also be obtained, but it will be observed that variations in manufacture are not as effectively taken care of, while the blade 5, being correspondingly shaped, also always has to be inserted with the same side up, in order for the slot edges therein to be received in the grooved edges in the member 6. In Figure 10, it will be noted that all beveling has been omitted from the blade, a vertical wall 25 and a horizontal wall 26 only being provided in the portion 6 and the blade being correspondingly shaped. Here also the desired guiding and a symmetrical construction will be obtained and it will be noted that the blade 5 may be reversed, if desired, but it will be noted that variations in manufacture are not as effectively overcome as in my previously described forms, while the blade is not as accurately positioned without expensive precision in manufacture.

In Figures 11 to 14, I have also shown a modified construction of guard, backing member and blade which may be used, if desired. In this construction, it will be noted that the same is essentially similar to that described in connection with Figures 1 to 8, save that, instead of a continuous connecting portion 6 wider than the diameter of the aperture 7, said portion comprises a plurality of spaced and narrower guiding parts 28 and these parts are spaced at opposite sides of an aperture 29 which is of greater diameter than the width of these parts 28. Further, it will be noted that the inner ends of the parts 28 are provided with portions 30 sloping downward to the top face of the guard and terminating just short of the opposite sides of the aperture 29. Here also it will be observed that while the grooves 31 in these parts 28 correspond generally to the grooves 11 heretofore described, these grooves are not continuous, being spaced by an intermediate open portion formed by the sloping portions 30, and further are provided with flared mouths at each end of each of the four grooves thus provided. Obviously the blade 32 used with this construction may be essentially similar to that heretofore described and the cross section of the grooves 31 and of the edges of the slot in the blade may be as heretofore. However, the slot 33 in the blade is narrower and an opening 34 is provided intermediate the ends of the slot to register with the aperture 29 when the blade is in the shaving position on the guard illustrated in Figure 11. Obviously, this construction will function generally similarly to that heretofore de-

scribed, although some additional manual guiding of the blade may be desirable in directing the end thereof over the gap between the parts 28 and the recess edges into the grooves 31 on the opposite side of this gap.

Here it will be understood that, while I prefer the use of a simple straight slot 15 in the blade, the edges of the slot may be cut back or indented along their length while obtaining certain of the advantages of my improved construction, provided, at the edges of the longitudinal opening therein, guiding portions of sufficient number or extent are provided to permit the blade to continue to be effectively guided and positioned in the grooves in the connecting means. Further, it will be understood that I contemplate the use of my improved blade supporting and connecting means in connection with other razors or cutting devices than those illustrated, and irrespective of whether the blade is flexed as herein, or remains unflexed during use.

While I have herein specifically described certain forms which my invention may assume in practice, it will be understood that these forms of the same are chosen for purposes of illustration and that the invention may be modified and embodied in various other forms without departing from its spirit or the scope of the appended claims.

What I claim as new and desire to secure by Letters Patent is:

1. In combination, a holder having raised connecting means thereon longitudinally grooved along its opposite sides, a resilient blade having a longitudinally disposed recess of substantially the length of said connecting means and closed at its ends and receiving said connecting means, said means and recess having cooperating engaging portions obstructing vertical assembly in all longitudinal positions of said blade relative to said connecting means, and said connecting means and recess also having cooperating means at their opposite ends for enabling insertion of the edges of said recess in said grooves from either end of said connecting means.

2. In combination, a holder having raised longitudinally disposed connecting means longitudinally undercut in its opposite longitudinal edges to form grooves therein, a resilient blade having a longitudinally disposed recess closed at its ends and receiving said portion and having portions narrower than all portions of the top of said raised connecting portion and also having recess edges disposable in said grooves, and means on said blade and connecting means including enlarged opposite ends of said recess and open ends on the extremities of said grooves for enabling like longitudinal insertion of said blade in assembled relation on said connecting means from either end of the latter.

3. In a razor, a guard having raised connecting means including parts extending from intermediate the ends of said guard longitudinally toward the ends thereof and having opposite longitudinally grooved sides, a resilient blade having a longitudinal recess and having longitudinal edges of said recess receivable in said grooves, said recess being widened at its opposite ends and said connecting parts being longer than the length of either of said widened ends of said recess.

4. In combination, a holder having a raised connecting portion longitudinally grooved along its opposite sides, a cooperating resilient blade having a longitudinal recess of substantially the

length of said portion receiving the latter and having recess edge means positionable in the groove means therein, and cooperating means on said blade and portion including laterally enlarged end portions of said recess and longitudinal grooves in the opposite ends of said connecting portion for enabling longitudinal insertion of said blade on said portion from either end of the latter and having the ends of said recess and the ends of said connecting portion engageable following such insertion to maintain said blade against substantial longitudinal displacement in either direction beyond the ends of said connecting portion.

5. A blade holder having a raised longitudinal connecting portion thereon longitudinally grooved along its opposite sides, said holder having blade supporting surfaces along the grooved sides of said connecting portion and said grooves having upper overhanging walls and downwardly sloping lower walls leading to said surfaces and extending laterally beyond the overhang of said upper overhanging walls.

6. In combination, a holder having a raised blade connecting and positioning portion spaced from opposite longitudinal edges of said holder and longitudinally grooved along its opposite sides, a cooperating resilient blade connectible to said portion and having a longitudinal recess of substantially the same length as said raised portion and recess edge means longitudinally receivable in the groove means in said connecting portion from either end of the latter when either end of said blade is flexed upwardly, and means operative on return flexure of said end for connecting said elements to one another following relative longitudinal movement of said blade and said connecting portion including substantially symmetrical connecting and positioning extremities on opposite ends of said connecting portion and also including cooperating substantially symmetrical positioning and connecting means forming the opposite ends of said blade recess.

7. In a razor, a guard having a longitudinally extending raised blade connecting portion and longitudinally extending blade receiving grooves on opposite sides of said portion, and a backing member cooperating with a blade disposed in the grooves in said portion in positioning the blade for shaving and having a recess of substantially the width of said portion and conforming to and receiving said portion, and means on said backing member having outer edge portions for flexing the outer edges of a blade disposed in the grooves in said connecting portion and also having inner edge portions extending along opposite longitudinal edges of said recess substantially throughout the length thereof and engaging the portions of the blade adjacent and projecting from the grooves in said connecting portion clamping said blade portion to the guard.

8. In a safety razor, a guard having a raised longitudinally disposed connecting portion and grooves in the opposite sides of said portion extending from intermediate the ends thereof longitudinally to the ends thereof, and a blade insertable into connected position on said portion from either end of the latter by movement in one longitudinal direction only and having a longitudinal recess having like enlarged opposite ends and of substantially the length of said portion and adapted to receive said portion with the ends of the latter adjacent the ends of said recess, said blade being transversely flexible at

opposite ends of said recess and having opposite edge portions received longitudinally in said opposite grooves and also having closed ends at opposite ends of said recess disposed adjacent opposite ends of said connecting portion and each disposable over and movable along over said connecting portion from either end thereof while said edge portions enter and move in said grooves.

9. In a safety razor, a guard having a raised connecting portion having substantially symmetrical remote ends and longitudinally grooved along its opposite sides, and a blade having a longitudinal recess for receiving said portion and of substantially the length of the latter and transversely flexible at each end of the recess therein and also having an enlarged opening at each end of said recess receiving either end of said connecting portion and intermediate edge portions having their ends exposed by said openings and receivable in the opposite grooves of said connecting portion, said grooves in said connecting portion extending substantially to opposite ends of said portion and having longitudinally disposed mouths at their opposite ends flared upwardly in the direction of flexure of the blade end for facilitating initial insertion of said exposed ends on the blade.

10. In combination, a holder having a raised connecting portion having longitudinally extending grooves on opposite sides thereof, a cooperating blade having a longitudinal recess and recess edges positionable in the grooves in said portion, cooperating variation compensating means between the grooves in said connecting portion and the edges of said recess including downwardly and outwardly directed surfaces on said grooves and cooperating surfaces on the edges of said recess, and a backing member carried by said holder and carrying means engaging said blade along and adjacent said cooperating surfaces for pressing said cooperating surfaces on said blade down on the downwardly and outwardly directed surfaces on said grooves in the direction of the clamping pressure to center said blade on said connecting portion.

11. In a safety razor, a guard having a raised connecting portion longitudinally grooved on opposite sides thereof, a blade having a longitudinal recess and recess edges positionable in the grooves in said connecting portion, cooperating variation compensating means between the grooves in said connecting portion and the edges of said recess including downwardly and outwardly directed bevelled groove edges and cooperating edges on said recess engaging with said bevelled edges, and means acting on said blade along said cooperating edges for pressing the edges on said blade down on the bevelled edges of said grooves in the direction of clamping pressure to center said blade on said connecting portion.

12. In a safety razor, a guard having a raised connecting portion longitudinally grooved on opposite sides thereof, a longitudinally recessed blade transversely flexible at each end of the recess therein and having a widened opening at each end of said recess receiving either end of said connecting portion, and intermediate edge portions receivable in the opposite grooves in said connecting portion, said grooves having downwardly and outwardly directed surfaces and said recess having oppositely directed surfaces on its opposite edges both on the top and on the bottom of said blade selectively cooperating with said downwardly and outwardly directed surfaces on said connecting portion in inverted positions

of the blade, and means acting on said blade along said recess edges for pressing the latter down on the surfaces on said grooves in the direction of the clamping pressure to center said blade on said connecting portion.

13. In a razor, a guard having raised longitudinally disposed connecting means thereon and longitudinal grooves in its opposite longitudinal edges, and a resilient blade having a longitudinal recess therein and having recess edge portions disposed in said grooves and terminating therein short of both opposite ends of said grooves and of said connecting means, and said blade also having enlarged end recesses communicating with said longitudinal recess and exposing both opposite ends of said recess edge portions and said enlarged recesses having end walls substantially abutting the opposite ends of said connecting means.

14. In a safety razor, a guard having a raised connecting portion having symmetrical opposite ends and grooves in the opposite sides of said portion extending from intermediate the ends of said connecting portion to the ends thereof, and a longitudinally recessed blade transversely flexible at each end of the recess therein and having closed ends spaced by substantially the length of said connecting portion and a laterally enlarged opening at each end of said recess receiving either end of said connecting portion and also having intermediate edge portions shorter than said grooves and receivable in the opposite grooves of said guard from either end of said connecting portion.

15. In a safety razor, a guard having a raised connecting portion grooved along opposite sides thereof and a longitudinally recessed blade transversely resilient and closed at each end of said recess and having a laterally enlarged opening forming each end of said recess and intermediate edge portions receivable in the opposite grooves of said guard, said connecting portion having means for connecting said blade to said raised portion upon longitudinal insertion of the blade from either end of said guard by longitudinal movement in one direction only and said grooved connecting portion also comprising cooperating longitudinally spaced parts having oppositely directed downwardly and inwardly inclined adjacent end faces for deflecting said closed end portions when moving in either of opposite directions between said spaced parts.

16. In a safety razor, a blade holder having raised connecting means thereon including parts extending from substantially midway between the ends of said holder substantially to the opposite ends thereof, and also having longitudinal grooves in the opposite longitudinal sides of said parts extending to the outer ends of the latter and having upper and lower blade confining walls, and a resilient blade of a thickness less than the height of said raised connecting means having a longitudinally disposed recess closed at its ends for receiving said connecting means and also having edge portions on said recess substantially as thick as the height of said grooves and substantially filling said grooves and maintaining said edge portions vertically centered in the plane of said grooves.

17. A resilient blade transversely flexible adjacent its ends and having a longitudinally disposed recess cut out therein between closed ends thereof, recess edge portions on the opposite sides of said recess between said ends, and upwardly and inwardly directed blade centering surfaces

along the innermost portions of the confronting edges of said recess for centering the blade relative to correspondingly upwardly and inwardly directed surfaces on a holder when the blade is clamped to the latter.

18. A resilient blade transversely flexible adjacent its opposite ends and having a longitudinally disposed cut out recess therein having closed ends and oppositely directed elongated blade centering surfaces on opposite longitudinal recess edge portions sloping toward the longitudinal center line of the blade, and extending along opposite longitudinal cut edges of said recess for engaging cooperating oppositely directed surfaces on a blade holder and centering the blade laterally when in use on such a holder.

19. A resilient blade having a longitudinally

disposed recess cut out therein and relieved oppositely directed blade centering top surfaces and like relieved oppositely directed blade centering bottom surfaces on the recess edge portions along each of the opposite longitudinal sides of said recess.

20. A resilient blade having a longitudinally disposed recess cut out therein and having closed ends and recess edge portions along each of the opposite longitudinal sides of said recess and each having oppositely directed beveled top edge portions and oppositely directed beveled bottom edge portions also oppositely directed with respect to said top edge portions, and an intermediate edge between said top and bottom beveled portions.

PAUL L. PHILLIPS.
